UNITED STATES PATENT OFFICE.

RUSSELL M. ANDERSON, OF KANSAS CITY, MISSOURI, ASSIGNOR TO PREMIER CUTLERY, INC., OF NEW YORK, N. Y.

TWEEZERS.

Application filed December 1, 1927. Serial No. 237,036.

My invention relates to tweezers of the character employed in barber and beauty shops for plucking hairs from the person, and my object is to provide an instrument 5 of this character in which the jaws are so formed that a hair may be readily and firmly gripped preparatory to being pulled from the person.

With the average tweezers it is not always 10 easy to take hold of a hair and after one has been grasped it frequently slips between the jaws of the tweezers when an effort is made to pull the hair from its follicle.

In order that the invention may be fully 15 understood, reference will now be had to the accompanying drawing, in which:

Fig. 1 is a side elevation of a pair of tweezers embodying the invention.

Fig. 2 is an enlarged broken sectional view 20 showing the two jaws of the tweezers grasping a hair.

Fig. 3 is a broken detail of one of the arms of the tweezers provided at its free end with a protuberance.

Fig. 4 is a broken detail of the other arm 25 of the tweezers provided at its free end with a socket for receiving the protuberance.

Fig. 5 is a broken detail showing a modification of the protuberance and the socket.

Referring in detail to the different parts, 30 1 designates a pair of tweezers consisting of a pair of arms 2 and 4 connected at one end in any suitable manner, such, for instance, as indicated at 6. The free end of the arm 2 is provided with a jaw in the form of a suitable protuberance 8 which is adapted to enter a companion jaw having a socket or cavity 10 at the free end of the arm 4. The socket or cavity 10 is open at one end only 35 for the reception of the protuberance 8 and to have a rim which will coat with said protuberance 8 in clamping a hair.

Preferably, the protuberance 8 is of spherical-like form and the inner surface of the 40 socket or cavity 10 is formed to receive said protuberance 8.

In practice when it is desired to pluck a hair it is only necessary to grip the latter firmly between the protuberance 8 and the

socket or cavity 10 and pull outwardly until 50 the hair is withdrawn from its follicle. As shown by Fig. 2, when gripping a hair the latter is forced into the socket 10 by the protuberance 8 and a firmer grip is obtained than is possible with the ordinary jaws 55 with which tweezers have heretofore been equipped. It is also apparent that the hair cannot be cut off as there are no sharp corners on the jaws as in the old style of tweezers.

In the modification Fig. 5, the protuberance 8^a is in the form of a solid cone and the socket 10^a is in the form of a hollow cone to receive said protuberance 8^a.

From the foregoing description, taken in 60 connection with the drawing, it will be understood that a hair can be readily grasped and by forcing it downwardly into the sockets 10 or 10^a with the protuberances 8 or 8^a, said hair can be firmly held so that it cannot 65 slip from between the jaws during the act of pulling the hair from its follicle.

From the foregoing description it is also apparent that I have provided a pair of tweezers which are more efficient than 70 75 tweezers having ordinary jaws with flat sides, and while I have shown two forms of the invention I reserve all rights to such other forms and modifications as properly fall within the spirit and scope of the invention as claimed.

Having thus described my invention, what I claim and desire to secure by Letters Patent, is:

1. A pair of tweezers consisting of two 80 connected arms, a protruding jaw mounted upon one of said arms, and a jaw mounted upon the companion arm and having a cavity open only at one end for the reception of said protruding jaw.

2. A pair of tweezers consisting of two 85 arms united at one end, a spherical jaw projecting from the free end of one of said arms, and a hollow jaw formed upon the free end of the companion arm and into which said protruding jaw is adapted to enter.

In testimony whereof I affix my signature.

RUSSELL M. ANDERSON.
